UNITED STATES PATENT OFFICE.

FREDERICK R. FULLER, OF NORTH GRAFTON, MASSACHUSETTS, ASSIGNOR TO UNITED SHOE MACHINERY COMPANY, OF PATERSON, NEW JERSEY, A CORPORATION OF NEW JERSEY.

VAMP-CUTTER.

1,034,704.

Specification of Letters Patent. Patented Aug. 6, 1912.

Application filed June 29, 1908. Serial No. 440,818.

To all whom it may concern:

Be it known that I, FREDERICK R. FULLER, a citizen of the United States, residing at North Grafton, in the county of Worcester 5 and State of Massachusetts, have invented a new and useful Vamp-Cutter, of which the following is a specification.

This invention relates to a cutter or die, which while certain features thereof are 10 adapted for general use, is especially designed for cutting vamps.

The principal objects of the invention are to provide a reversible die which can be operated from either side so as to cut rights 15 and lefts; to provide a construction in which a handle or block for receiving the blow or pressure during the cutting operation will be firmly secured to the die in such a manner that the points where the greatest strain 20 comes will consist of removable pieces that can be replaced when worn or damaged; to provide an improved form of guard for the die which will be strong and light, will be reversible, and will have means for returning 25 the die to central position after it has been operated; to provide a detachable tip-forming die which can be readily applied to a short vamp die; to provide convenient and simple markers for a die; and generally to 30 improve and simplify the construction and operation of cutters for dying-out blanks from sheet material such as upper leather for boots and shoes.

Further objects and advantages of the 35 invention will appear hereinafter.

Reference is to be had to the accompanying drawings which show a preferred form of the invention, and in which—

Figure 1 is a plan thereof; Fig. 2 is a sectional view on the line 2—2 of Fig. 1. Fig. 3 is an end elevation looking in the direction of the arrow 3 in Fig. 1; Fig. 4 is a side elevation in the direction of the arrow 4 of Fig. 1; Fig. 5 is an elevation of a portion of the inside showing one feature of the invention; Fig. 6 is a sectional view of the same; Fig. 7 shows part of a blank which has been marked by the markers illustrated in Fig. 5; Fig. 8 is a perspective view of a detail; and Fig. 9 is a fragmentary plan of a detachable tip die and guard.

The invention is illustrated in a form comprising a reversible die 10 having top and bottom cutting edges, so that the die

can be turned over and will cut right vamps 55 or the like on one side and left vamps on the other. The die herein illustrated has cutting edges shaped to die out a short vamp, that is to say, a vamp exclusive of the tip portion. In shoes of the type for which a 60 vamp cut by the present die is intended, the tip is cut out by a separate die and afterward stitched to the vamp. This die is provided with a frame 11 consisting of a plurality of arms, each secured to the die so 65 that a block or handle 12 may be inserted in a perforation 13 in the frame on either side, so as to receive a blow from a hammer or pressure from a press, to cause the die to cut through leather or similar material. In 70 the case of handle dies it will be understood that a strong frame is required, and that it must be firmly secured to the die. Ordinarily frames of this character are secured through the die or otherwise secured directly to it, and it has been found in practice that such a construction is not very durable on account of the hard usage to which the device is put. The screws or other fastening devices soon wear out and 75 also wear or break the walls of the die, so that the whole device has to be thrown away before the die itself has begun to wear out. In order to avoid this, and at the same time provide a firm construction, the die is provided with a series of perforations 14 through the walls thereof and removable pieces or inserts 15 are placed in them at 80 the ends of the arms of the frame and screwed to said ends. As the pieces 15 exactly fit the perforations 14, and as they are firmly secured to the ends of the arms, 85 it will be seen that a firm attachment of the frame to the die is secured, and yet if the screws or holes wear it is necessary only to 90 replace the pieces 15. These pieces have a long bearing surface on the top and bottom of the perforations 14, so that the latter do not readily wear out or get out of shape. It 95 will be understood, of course, that the die 100 and frame are both reversible, so that they can be operated from either side.

In order to properly hold and guide the die and guard its cutting surface against accidental injury, a guard or holder 20 is 105 provided. This guard corresponds in contour to the outside of the die, and it is formed in such a way as to secure lightness

of construction without sacrificing strength. This may be effected by making the guard of a more or less open character, preferably as illustrated in Fig. 4, by providing struts 5 or posts 21 separated by elongated perforations.

In order to provide for automatically returning the die to a central position after it has been operated in either direction, 10 springs 22 are mounted on certain of these posts and are provided with slots 23 through which project pins 24 mounted on the die. These pins work in slots 25 in the guard.

In order to provide in one structure for 15 cutting out short and full vamps, that is, vamps both with and without the toe tip, the guard is provided with a removable bow-shaped member 26 at the front, and the die with a removable piece 27 at the same point.

20 The bow-shaped member 26 is fastened to the guard 20 by angle pieces 28. The main part of the die which is shaped to cut out marginal edges of the vamp has a fixed bridge member 29 which is not provided 25 with a cutting edge, but which constitutes part of the die to receive the arms of the frame and to hold the latter on the die. When it is desired to change from the form shown in full lines in Fig. 1 to that shown 30 in dotted lines, the parts 26-27, and 28 are removed and the toe tip cutting die is mounted in position. This consists of a cutting member 30 shaped to cut the marginal edges of a tip and a frame piece 31,

35 the latter being secured by means of screws or bolts or in any other convenient manner to the bow-shaped piece 29. Outside of the cutting member a removable guard piece 32 is secured to the main guard by means of 40 cleats 33 or the like and proper fastening devices.

For the purpose of providing marks to indicate the size of the blank cut out and the proper location for the line of stitching 45 for the tip, the die is provided with two double-pointed markers or punches 34 and 35, each one movable with the die, but adjustable along the same so as to provide for changing its position. The marker 34 is 50 designed to show simply where the seam is to appear when the blanks are stitched together or the amount by which the tip should overlap the vamp, and therefore is provided with pointed ends so as to make a 55 small prick mark on the leather. The marker 35 is for indicating sizes and is provided with a cutting edge at each end of some characteristic shape to distinguish it from the mark made by the other die. Two 60 or more of the markers 35 may be used in order to indicate different sizes. It will be understood, of course, that the different sizes may be indicated either by the shape of this marker by the number which are employed. Both markers are mounted by 65

means of bolts or screws 36 in a slot 37 on a bar or plate 38 which is fixed to the die and moves therewith. The cutting edges or points of the markers are in the same plane as the cutting edges of the die. These markers are conveniently mounted on the inside of the die near the bow shaped piece 29.

The provision of longitudinally adjustable markers is of great advantage in combination with a die adapted for cutting out either short vamps or full vamps since it is frequently desirable to shift the location of the toe tip seam in changing from a short 75 to a full vamp.

While I have illustrated and described a preferred embodiment of the invention, I am aware that many modifications may be made therein by any person skilled in the art, and that many features thereof may be 80 applied to other kinds of dies or cutters, as for example, top dies, quarter dies, etc. without departing from the scope of the invention as expressed in the claims. Therefore I do not wish to be limited to all the 85 details of construction shown, but 90

What I do claim is:

1. In a cutter, the combination with a vertically movable die, of a guard therefor comprising a vertical surrounding wall open 95 at the top and bottom, said die being open clear through the same, whereby the inner edge of the die can be seen all around from the top of the guard.

2. In a cutter of the class described, the 100 combination with a vertically-movable, reversible, double die formed of a vertical member open at the top and bottom, of a reversible guard therefor also open at the top and bottom and surrounding said die. 105

3. A vamp cutter comprising a guard or holder, a die of substantially the same contour fitting the inside thereof, and having openings therein, a frame inside the die and pieces removably secured to the frame and fitting in said openings to hold the die on the frame. 110

4. A cutter comprising a guard or holder, a die movably mounted therein, fitting the inside thereof, and having openings therethrough, a frame inside the die having arms, and pieces secured through said openings to the ends of said arms to hold the die on the frame. 115

5. In a cutter, the combination of a guard 120 or holder, a die movable therein, and having openings through the walls thereof, a frame inside the die, and means located in and fitting said openings and positively secured to the frame for holding the die 125 thereto.

6. In a cutter, the combination of a guard or holder, a die movable therein, and having openings through the walls thereof, a frame inside the die, means located in and fitting 130

- said openings and positively secured to the frame for holding the die thereto, and springs on the guard for normally withdrawing the die inside the guard.
5. A vamp cutter comprising a reversible guard or holder, a double edged die movably mounted therein, and springs mounted on the guard and directly connected at their ends with the die for normally withdrawing the die inside the guard from each side and holding it centrally therein. 70
10. A vamp cutter comprising a guard, a die therein, a handle or block for receiving a blow or pressure to move the die in the guard, and means supported on the outside of the guard and directly connected to the die for returning the die to the center of the guard. 80
15. A vamp cutter comprising a guard, a die movably mounted therein for the vamp, and a toe cutting die removably secured to said die. 85
20. A vamp cutter comprising a reversible guard or holder, a double edged die movably mounted therein, and a toe cutting die removably connected with said die. 90
25. In a cutter, the combination of a vamp cutting die, a guard therefor and a toe cutting die and guard attachable respectively to the vamp cutting die and guard. 95
30. A vamp die having parallel edges sharpened for cutting right or left vamps, an unsharpened bridge member, and a toe tip cutting die removably secured to said bridge member and having cutting edges which extend continuously with those of the vamp die. 100
35. A vamp die having a cutting edge shaped to cut the marginal edges of a short vamp, a securing member rigidly connected with said vamp die at the toe end thereof, a toe tip cutting die, and provision for removably securing said die to the vamp die thereby forming a die for cutting full vamps. 105
40. A vamp die having a cutting edge shaped to cut the marginal edges of a short vamp, a toe tip cutting die shaped to cut the marginal edges of a tip blank, and means for removably securing said toe tip die to said vamp die in such relation that the cutting edges thereof extend continuously with those of the vamp die. 110
45. A device for cutting upper leather comprising a member having cutting portions, and a bridge member connecting said cutting portions, in combination with a supplementary cutting member and means for removably securing the latter to said bridge member and maintaining it in coöperating relation. 115
50. A cutting device of the class described, comprising a plurality of supplementary dying-out members having cutting edges and means for removably securing together said members with their cutting edges in alinement and forming a continuous cutting outline. 120
55. A die for cutting upper leather, having parallel edges sharpened for cutting right or left blanks, a slotted plate located intermediate of said cutting edges and extending longitudinally of said die and a double ended marker mounted on said slotted plate for adjustment longitudinally of said cutting edges. 125
60. A die for cutting sheet material having oppositely disposed cutting edges, a carrying bar secured to the die and spaced from its inner surface, and a plurality of separate double ended punches mounted upon the bar with their ends maintained substantially in planes of the respective cutting edges of the die and having provision permitting them to be adjusted to different points on the bar. 130
65. A vamp cutter comprising a main portion shaped to cut out the marginal edges of a short vamp, markers mounted on said portion and arranged for adjustment longitudinally of the cutting edge and a tip cutting portion removably secured to the main portion of the die. 135
70. A cutting die composed of two sections having cutting edges, the ends of which are adapted to register with each other, and are connected by stiffening members formed integral therewith, in combination with studs extending through openings in said members for locking the two sections together. 140
75. A cutting die composed of two sections having cutting edges, the ends of which are adapted to register with each other and are connected by stiffening members having contacting faces and perforations extending through one of said members at right angles to its contacting face; pins of the other member extending through said perforations; and means co-acting with said pins for locking the two sections together. 145
80. A cutting die composed of two sections, each having a cutting blade the ends of which are separated but permanently connected by a stiffening member integral with said blade; and means extending from one of said members to the other for locking said sections together with the ends of said blades abutting and in alinement. 150
85. A die for cutting sheet material having an edge sharpened for cutting, a carrier bar secured to the die and disposed in parallel relation to said cutting edge, and a plurality of separate punches mounted upon the carrier bar with their ends maintained substantially in the plane of said cutting edge in all positions on the bar and being so connected to the carrier bar as to permit of being moved into different positions longitudinally thereof. 155

24. A die for cutting sheet material having an edge sharpened for cutting, and a plurality of separate punching devices mounted within the die and maintained in line spaced from, and parallel to, the cutting edge and with their ends disposed substantially in the plane of the cutting edge, said punching devices being held rigidly against movement toward or from the cutting edge but having connections with the die permitting them to be set in different positions along the line in which they are arranged.

25. A die for cutting sheet material having an edge sharpened for cutting and a

plurality of openings formed at separate points in its sides, a pressure receiving member, and a connecting frame secured to the pressure receiving member and having removable pieces secured to its outer ends so shaped as to fit into the openings in the sides of the die.

In testimony whereof I have hereunto set my hand, in the presence of two subscribing witnesses.

FREDERICK R. FULLER.
